UNITED STATES PATENT OFFICE.

THOMAS IRVING POTTER, OF EAST ORANGE, NEW JERSEY, ASSIGNOR TO FEDERATED ENGINEERS DEVELOPMENT CORPORATION, OF JERSEY CITY, NEW JERSEY, A CORPORATION OF DELAWARE.

REFRIGERATING APPARATUS.

Application filed September 15, 1921. Serial No. 500,757.

To all whom it may concern:

Be it known that I, THOMAS IRVING POTTER, a citizen of the United States, residing at East Orange, in the county of Essex and State of New Jersey, have invented certain new and useful Improvements in Refrigerating Apparatus; and I do hereby declare the following to be a full, clear, and exact description of the same, reference being had to the accompanying drawing, forming part of this specification.

This invention relates to refrigerating apparatus particularly adapted for use of ammonia as a refrigerating agent although as will be obvious other known refrigerating agents may be used in the apparatus adopted to illustrate the invention.

An object of the invention is to provide a refrigerating apparatus of simple and compact construction that is easily operated and maintained in proper working order.

A further object is to provide a refrigerating apparatus that may be proportioned to small capacity, the refrigerating agent being conveyed in liquid form from the generator to any distant point for refrigeration purposes and returned to the generator as a vapor, then condensed and again utilized without a power driven pump or the like, this feature rendering the present invention particularly adaptable for household and restaurant use.

In the accompanying drawings—

Figure 1 is an elevation, partly in section, showing the generator, condenser and heater assembled, and

Fig. 2 is a sectional view of the expansion or cooling chamber and illustrating the connections between the expansion chamber and that portion of the apparatus shown in Fig. 1.

The generator of the present invention comprises a gas-tight container 1 having secured therein a pipe coil 2, perforated at intervals, and extending through both the heads of container 1. The outlet pipe of coil 2 projects through the upper head of the container and is fitted with a check valve 3 from which valve a pipe 4 leads to a condensing coil 5 located within a condenser chamber 6, the lower end of the condenser coil 5 opening into a reservoir 7 for the accumulation of liquid flowing from said condenser.

Water, for condensing purposes, is supplied to the interior of condenser chamber 6 through a supply pipe 8 communicating with the usual service pipe and the water, after passing into the chamber 6 and cooling the condenser coil 5, is discharged from said chamber through a pipe 9 leading to suitable means for heating the water supplied through said pipe. In the present instance the heating means comprising a coil 10 connected at one end to the pipe 9 and positioned within a casing 11 having a burner and gas supply pipe 12 leading thereto, this construction being the same as the gas heater now in common use for heating water for household purposes. The opposite end of coil 10 is connected to a pipe 13 communicating with a second coil 14 also positioned in the container 1 of the generator and discharging through an outlet pipe projecting through the upper head of said container, the coils of pipe 14 being interposed between the perforated coils 2.

The refrigerating chamber may be a receptacle of any desired type but in the present illustration it is shown as comprising a brine tank 16 having an expansion or cooling chamber 17 located therein. The expansion chamber 17 has an entrance opening adapted to be opened and closed by an inwardly closing valve 18 located in a valve chamber 19 surrounding the entrance opening of the expansion chamber. Liquefied gas is supplied to the valve chamber 19 from the condenser reservoir 7 through a pipe 20 and to permit the liquefied gas to enter expansion chamber 17 valve 18 is normally held open by suitable means preferably in the form of an annular elastic diaphragm 22 secured in the bottom wall of chamber 17 and having the valve stem 21 of the valve 18 secured thereto. An elastic coil spring 24 on an adjusting screw 23 secured below the diaphragm, bearing against the underside of said diaphragm normally elevates the valve 18 from the entrance opening of the expansion chamber.

Valve 18 being normally maintained opened, liquefied gas will flow into the expansion chamber and will be vaporized therein. A pipe 25 leads from the expansion chamber to the pipe 2 in container 1. There is a check valve 26 in the pipe 25 which opens in the direction indicated by the arrow.

row. However, the gas will not flow into the coil 2 until the pressure in said coil is reduced below that in the chamber 17, as will be presently explained.

5 Liquefied gas will continue to flow into the expansion chamber until sufficient gas pressure has been accumulated to depress the diaphragm 22 and close valve 18. By means of the adjusting screw 23, the pressure 10 which the diaphragm 22 will support before closing the valve 18 may be varied at will.

In operation, chamber 1 of the generator is preferably filled with a suitable absorbent material such as dehydrated calcium chloride 15 and the latter is saturated with liquid ammonia. By removing the cap of check valve 26 and partially vaporizing the ammonia in chamber 1, the air may be displaced in the pipe coils 2 and 5, reservoir 20 7 and chamber 17, after which the system may be sealed by replacing the valve cap. Water is then admitted through pipe 8, a valve (not shown) being provided for controlling the flow of water therethrough, and 25 passing through the condenser chamber 6 and the heater coil 10 where it is heated, it passes upward into and through coil 14 in the generator and heats the contents of container 1. The liquid ammonia in said 30 chamber is thus vaporized, the accumulation of the vapors in the chamber creating sufficient pressure to drive off the vapors into and through coil 2 and check valve 3 and into the condenser coil 5 where it is 35 liquefied and collects in the reservoir 7.

The screw 23 having been adjusted 40 against spring 24 to lift valve 18 off its seat in the entrance opening of expansion chamber 17, the liquefied gas is free to flow under compression from reservoir 7 through 45 pipe 20 into the expansion chamber until sufficient pressure is developed by vaporization and displacement in said chamber to overcome, by pressure on the upper surface of diaphragm 22, the action of spring 24 and close valve 18.

After the ammonia has been driven off by 50 heat from the coil 14 and liquefied in reservoir 7, the heat is turned off from heating coil 10 and the water then flowing through the coil 14 in container 1 will be comparatively cool. Cooling of the contents of 55 container 1 will tend to create a vacuum, or in other words, reduce the pressure in the container below that in the expansion chamber 17 and the container and expansion chamber being in direct communication with each other through pipe 25 and check valve 26, the liquid ammonia in the expansion chamber will be vaporized and returned to the container 1 in the form of vapor, heat being abstracted from the chamber 17 and brine tank 16 during the expansion and evaporation of the ammonia as will 60 be readily understood. As the vapor is con-

70 densed and absorbed in the container 1, the pressure on diaphragm 22 will be lowered until the spring-pressed diaphragm is able to raise the valve 18 against the fluid pressure in the valve chamber 19, when more liquid will flow into the expansion chamber 17.

The vaporization will continue until the 75 temperature in brine tank 16, or other chamber bearing cooled, has been sufficiently lowered to arrest vaporization in chamber 17 or the liquefied ammonia has all passed from reservoir 7 into chamber 17 and on into chamber 1 and been re-absorbed in the calcium chloride. When the vaporized ammonia has been re-absorbed in container 1 80 heat is again applied to heating coil 10 and the process repeated.

It will be noted that coil 2 and a coil 85 14 are arranged in close proximity through the major portion of their length, this construction serving to greatly expedite the driving off and reabsorption of gases. In other words, the fact that the temperature controlling element is in intimate contact with that part of the refrigerating circuit which 90 communicates with the generator greatly adds to the efficiency and the speed of operation of the apparatus.

It will be evident that screw 23 serves not 95 merely to regulate the spring pressure in diaphragm 22 but also to control the temperature of the brine tank 16. The vaporization of the liquefied gas in the expansion chamber is produced by the heat from the surrounding brine. The lower the pressure in 100 the expansion chamber, the lower will be the boiling point of the liquefied gas. By adjusting the screw 23 so that valve 18 will close at a comparatively low pressure, the vaporization will continue until the temperature of the brine has been reduced to a correspondingly low temperature, while when the screw 23 is adjusted for a comparatively high pressure, vaporization will cease 105 when the temperature of the brine has been lowered to a correspondingly less extent.

110 What is claimed is:

1. In a refrigerating apparatus, a generator condenser and expander arranged in a closed refrigerating circuit, means for preventing back flow of refrigerant through 115 said circuit, said generator containing a non-liquid absorbent, said circuit including a refrigerant conducting pipe leading from the expander to the condenser through said generator and having a coiled perforated portion located within the generator, a pipe 120 for conducting temperature regulating fluid in said generator intercoiled with the perforated and coiled portion of said first mentioned conductor.

2. In a refrigerating apparatus, a generator, condenser and expander arranged in a closed refrigerating circuit, means preventing back flow of refrigerant through 125 said circuit.

circuit, said generator containing a non-liquid absorbent, said circuit including a refrigerant conducting pipe leading from the expander to the condenser through the generator and including a perforated portion located within the generator, a pipe in the generator for conducting temperature regulating fluid, said pipe being arranged in close proximity to the entire perforated portion of the first mentioned pipe whereby to expedite the absorption and emission of gases in said generator.

THOMAS IRVING POTTER.
